END STOP FOR SEPARABLE FASTENERS

Davis Marinsky, Bronx, N. Y., assignor to
Whitehall Patents Corporation, New York,
N. Y., a corporation of New York

Application August 24, 1937, Serial No. 160,568

4 Claims. (Cl. 24—265)

This invention relates to separable fasteners employing stringers adapted to be coupled and uncoupled by a slider movable longitudinally of the stringers, and particularly to an improved end stop construction for devices of this class which will facilitate the attachment of the stringers to their supports, and the proper assemblage of the fastener stringers one with respect to the other; and the object of the invention is to provide an end stop in the form of a double channelled body into the separate channels of which the stringer tapes are adapted to be attached and secured, and especially wherein said body is of such cross sectional form as to enter the channel in the contracted end of the slider in the limited movement of the slider in the direction of said stop, with means on the stop for limiting the movement of said slider thereon; a further object being to provide a stop of the class described, one side channelled portion of which may be normally left open for receiving an opposed stringer in the operation of coupling the stringers together, the walls of said channelled side being of irregular contour to securely engage the stringer tape; a further object being to provide a coupling of the class described composed of a die cast body, the outer end portion of which is provided with a protruding stop flange for limiting the movement of the slider in one direction thereon; a still further object being to provide a device of the character described wherein means is provided for automatically engaging the stringer tape to prevent movement of the stop on said tape in one direction; and with these and other objects in view the invention consists in a device of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic view showing the separate stringers of a fastener made according to my invention detached with parts of the construction broken away and in section.

Fig. 2 is a view similar to Fig. 1 showing the parts attached and eliminating a part of the construction.

Fig. 3 is a partial section on the line 3—3 of Fig. 1 on an enlarged scale.

Fig. 4 is a partial section on the line 4—4

of Fig. 2 omitting the slider shown in Fig. 2, the section being on an enlarged scale.

Fig. 5 is a perspective view of a modified form of end stop which I employ and illustrating the same attached to part of one stringer; and

Fig. 6 is a section on the line 6—6 of Fig. 5 and illustrating a part of a stringer arranged in the end stop.

In the use of separable fasteners of the kind under consideration, problems have been experienced in the attachment of the stringers to various supports, such for example as in mounting the stringers in connection with pocketbooks, on trousers, and in other uses, especially from the standpoint of attaching the stringers and maintaining proper alinement and arrangement thereof. It is the purpose of my invention to provide a means of constructing these stringers and assembling the same so as to provide for the independent attachment of the stringer tapes to the respective supports and to provide a simple and practical means for coupling the stringers together and to maintain and assure proper alinement thereof as will later appear.

In Fig. 1 of the drawing I have shown for the purpose of illustrating one method of carrying my invention into effect, parts of two supports 7 and 8 to which the stringer tapes 9 and 10 are secured. Each stringer tape has, preferably, a beaded edge to which the coupling links or scoops 11 and 12 are attached. These scoops may be formed and mounted in any desired manner, and consists of die castings of the metal or thermoplastic groups.

At 13 and 14 I have shown on each stringer one of the end stops which limit the movement of a slider 15 in one direction on the stringers. The slider consists of the usual channelled body having the contracted end portion 15a and the flared end portion 15b. The latter end portion 15b has a V-shaped connecting web 15c which joins the top and bottom plates of the slider. One plate of the slider is provided with a member 16 providing means for supporting a finger piece or pull 17, part of which is shown in Fig. 1 of the drawing.

In Figs. 1 to 4 inclusive, I have shown at 18 one of my improved end stops which consists of a body portion having channels 19 and 20 at the side portions thereof and arranged longitudinally of said side portions. The channels 19 and 20 open outward through the sides of the body and form jaw members 21 where the channel 19 is arranged and jaw members 22 where the channel 20 is arranged. These jaw members normally

are widely separated, as indicated at the left of Fig. 3 of the drawing, when the device 18 is made so as to facilitate free insertion of the stringers 9 and 10, as will be apparent. The adjacent faces 5 of the jaw members 21 and 22 are provided with longitudinally spaced teeth or projections 21a, 22a which are adapted to extend into the braid of the stringer tapes 9 and 10 in securing the device 18 thereon.

10 The inner ends of the channels 19 and 20 are preferably flared to facilitate free insertion of the beaded edges of the stringer tapes 9 and 10. One of these flared ends is indicated at 23 in full lines in Fig. 1 of the drawing. The other 15 outer end of the end stop device 18 is provided with an outwardly projecting stop flange 24 which limits the movement of the slider 15 on the stringers and on the device 16. It is understood that the cross sectional contour of the device 18 forwardly of the flange 24 is such as to enter the contracted end 15a of the slider 15 as indicated in Fig. 2 of the drawing. It will thus be seen that said contracted end of the slider engages the flange 24 in limiting the movement 20 of the slider on said end stop.

In the use of the device shown in Figs. 1 to 4 inclusive, it will be understood that after the stringers have been formed with the links 11, 12 thereon and the end stops 13 and 14 attached, 30 the slider is then mounted upon one of the stringers, for example, the stringer 10 as shown, after which the stringers are attached or coupled together by the slider. When so coupled, the stop 24 is arranged on both stringer tapes 35 so as to bring the inner end of the stop 18 in engagement with the end link 11a of the stringer 9. The channel portion 19 of the end stop may then be firmly compressed upon the tape 10 in the manner shown, so as to retain said stop 40 against displacement from said tape. However, the other side having the channel 20, is left in its open position. The assembled fastener will now be suitably aligned on the respective parts 7 and 8 to which the stringers 9 and 10 are to be 45 attached. The tapes may be temporarily attached thereto in any desired manner after which the fasteners are separated by moving the slider 15 into the position shown in Fig. 2, and then drawing the stringer 9 through the 50 slider and the open channel 20 of the stop 18. The separate stringers 9 and 10 may then be stitched or otherwise secured to the support 7 and 8, as is indicated at 25, 25a. Then the stringers may be reassembled by threading the end 55 9a of the stringer tape 9 through the slider 15 when in a position similar to that shown in Fig. 2 and into the channel 20, after which the stringers are coupled together, and then the jaws 22 are compressed onto the tape 9 to secure 60 the stop 18 thereto to produce the result illustrated in Fig. 4 of the drawing. Any suitable tool or tools are used for this purpose. Aside from any other finishings that may be necessary in the different uses or assemblages of 65 the stringer tapes, the device is now ready for use.

In Figs. 5 and 6 of the drawing I have shown a slight modification of the construction shown in Figs. 1 to 4 inclusive, in which the end stop 70 18a is provided at one side with a channel construction 26 similar to the channel 19 in all respects, whereas substituted for the channel 20 is a channel 27. Adjacent surfaces of the jaws 28 are left smooth rather than being provided 75 with the teeth or projections. With this con-

struction, one wall of the stop 18 is provided with an aperture 29 which opens into the channel 27. Pivotally supported in the aperture 29 is a pawl 30 arranged upon a pin 31 transversing the aperture 29. A spring 32 is seated in the aperture and cooperates with the pawl 30 to normally project the pointed end 30a thereof downwardly into the channel, which movement of the pawl is restricted by a projection 33 on said pawl. The stop 18a also has the end flanges 10 24a similar to the flanges 24. With this type of construction the end stop 18a will be permanently attached to one stringer tape 34 which is arranged in the channel 26 thereof as indicated in Fig. 5, whereas the other stringer tape 35 will be slidable through the channel 27 from the right toward the left as viewed in Figs. 5 and 6 in the operation of coupling the same therewith. In this operation the stringer 35 or the beaded edge 35a thereof will automatically raise the 20 pawl 30 against the action of the spring 32. However, when the stop 18a reaches the end link 36 on the stringer 35, continuation of this sliding movement through the channel 27 is prevented by engagement between the stop and the 25 end link, and the pawl 30 will prevent movement in the reverse direction, since the pawl 30 or the pointed end 30a thereof will dig into the tape and secure or retain the stop 18a against outward movement thereon.

This construction will eliminate the necessity of using any kind or class of tools in making the attachment and may find its usefulness in the cases where the complete fastener is sold as a unit for individual use in what might be termed 30 the retail sale of devices of the kind under consideration. It will also appear that a novel method is provided for the attachment of fastener stringers to their respective supports which will greatly facilitate and simplify the manufacturer's problems of attaching fastener stringers to their respective supports.

It will be understood that my improved end stop may be composed of a die cast body which will be made in the form of a metallic casting 45 when the remainder of the fastener is of similar construction, but it will be made of thermoplastic material when the remainder of the device is constructed of such material.

It will also be apparent that my invention is 50 not limited to any particular type of stop used at the ends of the stringer to which the present stops 13 and 14 are secured. It will also be understood that the top and bottom surfaces of the walls of the end stop 18, 18a may be characterized to give ornamental appearance thereto, or in applying trade marks or other markings 55 thereon.

Having fully described my invention, what I claim as new and desire to secure by Letters 60 Patent is:

1. An end stop forming device for separable fasteners of the class described employing stringer tapes with coupling links on said tapes, a slider movable longitudinally of said tapes to 65 couple and uncouple said links and having means at one end of said tapes to limit the movement of the slider in one direction on the tapes, said device comprising a double-channelled body, one tape being permanently secured in one of said 70 channels retaining the slider against displacement from said tape, transversely arranged tooth means in the other of said channels whereby the other of said tapes may be inserted therethrough and retained against subsequent dis- 75

placement therefrom, and said end stop having a substantially peripheral slider engaging flange at the end thereof farthest removed from said links.

2. An end stop forming devices for separable fasteners of the class described employing stringer tapes with coupling links on said tapes, a slider movable longitudinally of said tapes to couple and uncouple said links and having means at one end of said tapes to limit the movement of the slider in one direction on the tapes, said device comprising a double-channelled body, one tape being permanently secured in one of said channels retaining the slider against displacement from said tape, means in the other of said channels whereby the other of said tape may be inserted therethrough and automatically retained against subsequent displacement therefrom, said last named means comprising a tooth-like prong pivotally arranged in said end stop and tensionally projected into said channel.
- 5 10 15
- 10 of the slider in one direction on the tapes, said device comprising a double-channelled body, one tape being permanently secured in one of said channels retaining the slider against displacement from said tape, means in the other of said channels whereby the other of said tapes may be inserted therethrough and retained against subsequent displacement therefrom, said means comprising spaced jaw members compressible onto said tape, and opposed surfaces of said jaw members having transverse teeth longitudinally arranged thereon.
- 15 20 25

3. An end stop forming devices for separable fasteners of the class described employing stringer tapes with coupling links on said tapes, a slider movable longitudinally of said tapes to couple and uncouple said links and having means at one end of said tapes to limit the movement of the slider in one direction on the tapes, said

device comprising a double-channelled body, one tape being permanently secured in one of said channels retaining the slider against displacement from said tape, means in the other of said channels whereby the other of said tape may be inserted therethrough and automatically retained against subsequent displacement therefrom, said last named means comprising a tooth-like prong pivotally arranged in said end stop and tensionally projected into said channel.

4. As an article of manufacture a single stringer of a separable fastener of the class described, said stringer comprising a tape having coupling links arranged at spaced intervals along one edge thereof, an end stop permanently secured adjacent the end links and a slider loosely supported by said links and retained thereon by said end stop, said end stop extending beyond the coupling portion of said links, a channel in the extending portion of said end stop substantially parallel to the edge of the tape, said channel opening through the ends and the projecting side of said end stop, and spring actuated detent means in said channel whereby the edge of a second stringer may be inserted therein and automatically retained against subsequent removal therefrom.

10 15 20 25

DAVIS MARINSKY.
